(57) **CLAIM**

The ornamental design for a smoke leak detector, as shown and described.

DESCRIPTION

FIG. 1 is a front, right, and top perspective view of a smoke leak detector, showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view taken from the encircled portion labeled "9" in FIG. 1;

FIG. 10 is an enlarged view taken from the encircled portion labeled "10" in FIG. 1; and,

FIG. 11 is an enlarged view taken from the encircled portion labeled "11" in FIG. 1.

The short-dash and long-dash broken lines in FIGS. 1, 9, 10, and 11 denote the boundaries of the detail areas and form no part of the claimed design. The evenly-dashed broken lines in the drawings depict portions of the smoke leak detector that form no part of the claimed design.
